UNITED STATES PATENT OFFICE.

OSCAR GUTHERZ, OF LIMOGES, FRANCE.

DESIGN FOR A CUSPIDOR.

SPECIFICATION forming part of Design No. 13,515, dated January 9, 1883.

Application filed November 16, 1882. Term of patent 7 years.

To all whom it may concern:

Be it known that I, OSCAR GUTHERZ, of Limoges, France, have invented a new and Improved Design for Cuspidors, of which the following is a full, clear, and exact description.

Reference is to be had to the accompanying drawings, forming part of this specification, in which similar letters of reference indicate corresponding parts in both the figures.

Figure 1 is a plan view of a cuspidor, illustrating my newly-invented design; and Fig. 2 is a sectional elevation of the same, taken through the line *x x*, Fig. 1.

15 The leading feature of my design consists in the triangular form and the truncated angles of the mouth and body of the cuspidor.

The mouth of the cuspidor is made flaring and triangular in its general contour, and may 20 have its sides *A* plain or slightly curved.

The corners *B*, formed by the intersection of the sides *A* of the mouth, are truncated, and the planes thus formed may be flat or slightly convex upon the upper side.

25 The body *C* of the cuspidor is also made triangular in its general contour and flaring from

its base upward for about one-third of its height, being in the form of an inverted frustum of a pyramid, and then contracts for the rest of its height, being in the form of a frustum of a 30 pyramid. The angles or corners *D*, formed by the intersection of the sides of the said body *C*, may be plane or slightly concaved upon the outer side, as shown in Fig. 1.

Having thus described my invention, what 35 I claim as new, and desire to secure by Letters Patent, is—

1. The design for a cuspidor-mouth herein shown and described, the same consisting of the triangular mouth having its sides *A* flaring and slightly curved and its angles *B* truncated.

2. The design for a cuspidor-body herein shown and described, the same consisting of the triangular body *C*, having its lower part 45 in the shape of an inverted frustum of a pyramid, its upper part in the shape of a frustum of a pyramid, and its angles *D* truncated.

OSCAR GUTHERZ.
